UNITED STATES PATENT OFFICE.

WALTER I. KIRK, OF CHICAGO, ILLINOIS, ASSIGNOR TO LYON & HEALY, OF CHICAGO,
ILLINOIS, A CORPORATION OF ILLINOIS.

TRUNK FOR HARP OR LIKE INSTRUMENTS.

1,352,814.

Specification of Letters Patent. Patented Sept. 14, 1920.

Application filed August 4, 1916. Serial No. 113,076.

To all whom it may concern:

Be it known that I, WALTER I. KIRK, a citizen of the United States, residing at Chicago, in the county of Cook and State of Illinois, have invented a certain new and useful Improvement in Trunks for Harps or like Instruments, of which the following is a full, clear, concise, and exact description, reference being had to the accompanying drawings, forming a part of this specification.

My invention relates to trunks for harps or like instruments.

Prominent objects of the invention are to provide a simple and practical trunk of the class specified which can contain and carry not only the harp, but also a chair and a platform for the operator or player, or either one of these additional articles; to secure this result without enlargement of the trunk, or injury to the trunk or the various articles carried thereby; and to secure the foregoing and other desirable results in a simple and expeditious manner.

In the accompanying drawings Figure 1 is a perspective view of a trunk of the class specified containing a harp, a chair and a harp platform, said trunk embodying my present invention;

Figs. 2 and 3 are elevations of the opposite sides of said trunk without the articles shown in Fig. 1;

Figs. 4 and 5 are sections taken on lines 4—4 and 5—5 respectively in Fig. 1.

The trunk shown in the drawings is composed of two parts 1 and 2 which are hinged together at 3 so as to make a case which may stand upright and is longitudinally divided into two similar parts of substantially harp shape. A harp 4 is shown within the part 2 which is the larger of the two parts, serving as a body portion, while the part 1 serves more as a cover. The harp 4 rests upon the base 5 in the body part 2. The latter is provided with blocks 6, 7, 8, 9, 10 and 11 secured to the various wall members of the part 2 and adapted to engage the harp 4 at various points and hold the same firmly in position. The part or cover 1 is provided with blocks 12, 13 and 14 secured to the flat side of said cover 1 and also adapted to engage the harp 4 at different points when the cover 1 is closed and thereby hold the harp from sidewise movement.

A chair 15 is shown mounted upon the flat

side wall of the body portion 2 and a platform 16 is shown mounted upon the flat side wall of the cover 1. The chair 15 and the platform 16 are especially adapted for use with harps or similar instruments, the platform being adapted to have the harp mounted upon it and also adapted to serve as a support for one end of the chair so as to maintain the chair in proper position relatively to the harp, and the chair being especially adapted for a harp or like instrument player, and also adapted for use in connection with the platform. This chair and platform are also especially constructed and adapted to permit of their being arranged and supported within the harp trunk so as to permit of their being shipped with the harp without the necessity of an additional package or trunk. This chair and platform are made the subject of separate applications for patent executed by me of even date herewith, said applications covering the chair and platform individually, the present application covering the trunk adapted and constructed for containing and mounting said chair and platform together with the same confined therein.

The chair 15 is shown in a collapsed form and supported upon the flat side member 2 in such collapsed form. Said side member is provided with suitable supporting and holding devices, those shown consisting of a pair of strips 18, 19, extending substantially parallel with one another and secured in position with a space 20 between them. The upper strip 18 is provided with a pivoted latch 21 which may be swung into the positions shown in Figs. 1 and 3. As shown in Fig. 1 a cross member 22 located between the lower ends of the front legs of the chair is placed in the space 20 and then the latch 21 is swung downwardly as shown in Fig. 1, so as to come on the outer side of said member 22 and thereby hold the same in position between the strips 18 and 19. The latter are preferably covered with felt or some similar material so as to prevent scratching or marring the cross member 22 or the legs 23 connected therewith. Straps 24 are also secured to the flat side member 2 of the trunk body 2, as for example by cleats 25, said straps 24 being provided with buckles 26. These straps are adapted and intended for use in strapping other portions of the chair in position, as for example the

lower ends of the front legs 23 when said ends are extended upwardly by the collapse of the chair and also the upper ends of the side portions 27 of the back 28. The flat 5 side of the portion 2 is also preferably provided with sockets 30-30 adapted to receive and hold the lower ends of the rear legs 31 of the chair. Thus it will be seen 10 that the chair in its collapsed condition may be mounted firmly in position in the trunk and in such position will not interfere with the harp, nor will any extra space be needed in the trunk, because the chair can fit in the space between the harp strings and the 15 flat side wall of the portion 2.

It will be understood of course that while the chair 15 is especially adapted to be collapsed and advantageously secured in position as herein set forth, I do not wish to 20 limit myself to the particular type of chair used nor to the particular devices for mounting the same, as it is obvious that changes and modifications may be made without departing from the spirit of the invention.

25 On the side wall of the other member 1 the platform 16 is shown detachably mounted in position, as conveniently by cleat members 33, 34 and 35. The cleat member 33 as shown in Figs. 1 and 2 is in the form 30 of a cross strip secured in position by screws 36 and having a longitudinally extending recess 37 into which can be fitted the pivoted or tilting end 38 of the platform 16. A 35 pivoted latch 39 is also provided and arranged to swing so as to engage and hold the cross member 38. The cleats 34 and 35 are adapted to receive edge portions of the platform 16 and engage the same, said cleats being positioned so as to properly engage 40 the lower end of the platform when the cross member 38 is in the recess 37 of the cleat or strip 33. It will be understood also in connection with this feature of the inven-

tion that other constructions of platforms could be confined and mounted in the trunk 45 and that other mounting devices could be employed without departing from the spirit of the invention. Other articles than those herein set forth could be arranged and held in position in the trunk. 50

From the foregoing it will be seen that the trunk is adapted to contain and transport not only the harp, but also the chair and platform for the same and that additional packages or trunks are therefore not 55 required, nor is it necessary to make the trunk unduly large or cumbersome in order to carry all of the articles mentioned. In fact harp trunks of the usual size and shape may be equipped with supporting and holding devices such as I have disclosed, thereby 60 securing the new and advantageous results mentioned in the old type of trunk or case.

It will be understood that changes and modifications may be made without departing 65 from the spirit of the invention.

What I claim is:

1. A trunk comprising a casing of substantially harp shape having one of its side walls provided with strips and fastening devices and also sockets for engaging a cross member and the legs of a chair. 70

2. A trunk comprising a casing of substantially harp shape having one of its side walls provided with parallel strips for engaging a cross member of a chair, a fastening device for holding said cross piece between said strips, and sockets for receiving the legs of said chair. 75

In witness whereof, I hereunto subscribe 80 my name this 30th day of June, A. D. 1916.

WALTER I. KIRK.
